United States Patent Office

Des. 221,165
Patented July 13, 1971

221,165

MODEL RACING CAR

Eric Harrison Broadley, Pangborne, near Reading, England, assignor to Lola Cars Limited, Trading Estate, Slaigh, Buckinghamshire, England

Filed Mar. 31, 1970, Ser. No. 22,140

Claims priority, application Great Britain Oct. 2, 1969

Term of patent 7 years

Int. Cl. D21—02

U.S. Cl. D34—15

FIG. 3

FIG. 4

FIG. 1 is a top plan view of the model racing car showing my new design; and

FIG. 2 is a front elevational view thereof; and

FIG. 3 is a right side elevational view thereof; the opposite side being substantially in mirror image thereof; and

FIG. 4 is a rear elevational view.

I claim:

The ornamental design for a model racing car, as shown.
